(57) **CLAIM**

The ornamental design for a nasal implant for rhinoplasty as shown and described.

DESCRIPTION

1.1 : Perspective

1.2 : Front

1.3 : Back

1.4 : Left

1.5 : Right

1.6 : Top

1.7 : Bottom

1.8 : Cross sectional

The material of the product is a medical synthetic resin such as silicone that is harmless to the human body; the product is used in plastic surgery on the nose to enhance the bridge of the nose and tip of the nose or modify the shape of the nose for cosmetic purposes; the creative part of the design is the shape and form of a nasal implant for rhinoplasty.
